UNITED STATES PATENT OFFICE

THOMAS HAROLD BROWN, OF LANSDOWNE BOROUGH, PENNSYLVANIA, ASSIGNOR, BY MESNE ASSIGNMENTS, TO NATIONAL SASH WEIGHT CORPORATION, OF BALTIMORE, MARYLAND, A CORPORATION OF MARYLAND

CORE-FORMING APPARATUS

Application filed October 26, 1926. Serial No. 144,208.

My invention is a one piece multiple core bars assembled in accordance with my invention; Fig. 2 is a side elevation of the core box and character bearing bars and wedging rods in position; the cross-piece or connector of the wedging elements and the screws therefor being shown detached from their normal relation to illustrate the manner of the assembly thereof; Fig. 3 is an end elevation of the assembled core-box and molding bars; Fig. 4 is a longitudinal section through the core-box with the molding bars in place on the line 4—4 of Fig. 1; Fig. 5 is a transverse sectional view on the line 5—5 of Fig. 1; Fig. 6 is a bottom plan view of the assembly shown in Fig. 1; and Fig. 7 is a perspective view of one of the group of cores formed by my improved core-box.

By my improvements, I am enabled to provide a portable multiple core box with cooperating gangs of character bearing bars and wedging bars and to effect the manipulation of such gangs as units by utilizing as handles the cross bars connecting together the members of the respective gangs. I also secure accurate positioning in the box cavities of the characters on the moulding bars of one gang by the provision of limiting stops detachably locked in place by the moulding bars of the other gang; and the positioning and retention of the moulding bars of each gang relatively to one another and to the lateral apertures of the boxes is attained by an improved method of assembly and attachment of parts. As a result of my improvements, a sand blowing machine may be utilized for supplying and packing sand in the core box, the output of cores is greatly increased, the quality of the cores greatly improved, and there is less breakage and damage than where single cavity core boxes are used in cooperation with anchored moulding bars.

The characteristic features and advantages of my improvements will further appear from the following description and the accompanying drawings in illustration of a preferred embodiment of my invention.

In the accompanying drawings, Fig. 1, is a top plan view of a core-box and moulding

In its preferred form, my invention is embodied in a single piece core box preferably formed of a block or casting 11 containing a series of pairs of core-cavities 12, evenly spaced in the box and separated by webs 13. For lightness, the bottom of the box may consist of a pair of longitudinally extending ribs 14; side-concavities 15 may be formed between the bosses or supports 16 which are aligned vertically with the top of the casting, and concavities 18 may be formed in the end walls 17, from which project handles 20. The box may rest upon the longitudinal ribs as a stand or support, and be conveniently manipulated by the handles 20, but it is manifest that the exterior contour of the box is of relatively little importance.

The core to be formed preferably comprises a cylindrical barrel A and curved bridge B spaced by the eye or opening C, the surface E of such opening having a character D impressed therein. To give such shape to the cores the cavities 12 of the box have cylindrical upper sections terminating at the bottoms in grooves 21 disposed in the ribs 14. The opening C is formed in the core and the character D impressed upon the surface E thereof by molding bars comprising tapered character bearing bars 22 and cooperating wedge members 23.

The molding bars are inserted into the cavities 12 from opposite sides of the box through openings 24 cut or formed through the mem-

bers 16 and through the intermediate webs 13 separating the cavities of each pair. Each opening preferably has a flat upper edge or surface 25 and a rounded or curved lower surface 26. The axis of a series of three aligned openings passes diametrically through a pair of core cavities as shown.

The free end of each bar 22 has a lip or stop 27 thereon. Each such bar is tapered so that its flat character-bearing face 28 and its flat lower face 30 diverge toward the end of the bar opposite the lug 27 where it terminates in a laterally enlarged tang 36 for connection with a cross piece or handle 31. The upper surfaces 28 of the bars have formed in relief thereon characters 32 arranged for location substantially in the centers of core cavities when the bars are properly positioned. Each stop 27 is spaced the width of the box from the lug 33 formed on each bar and the characters 32 are so located on the bar that when the stops and lugs engage the opposite sides of the box the characters are accurately positioned relative each core cavity.

In operation, the bars 22 are slid endwise through the registering openings until the lugs 33 abut one wall and the lugs 27 have cleared the opposite wall. The lugs 27 will be tilted upward by the weight of the opposite ends of the bars 22 and the connector 31 therefor, and the bars 22 are elevated and locked in position by the inward movement of the bars 23.

Each wedging bar has a flat upper surface 23', and a rounded lower surface 34, slideable in the rounded portions 26 of the lateral openings 24, and tapered so as to compensate for the taper of the character bars. Each wedge bar terminates at the free end in a laterally enlarged tang 37 similar to the tang 36 of the bars 22.

To secure the bars 22 and 23 in gangs which will register with the lateral openings of the box, it is desirable that they initially be assembled in the box and while so positioned secured in gangs by cross pieces or handles 31 preferably having longitudinal lips or flanges 35 arranged to extend over the tang ends of the elements. The handles and bars may be held in proper position while several holes 38 and 40 are drilled through each gang and the cross pieces. Screws or bolts 41 passing through the apertures and held by nuts 42 permanently secure the several sets of bars to the respective cross pieces. The assembly of the gangs of bars for a particular box may thus be suited to the alignment of the box openings without necessity for the accurate machining and drilling required to secure registry where the bars are assembled in gangs apart from the box.

By my improvements, the production of cores is greatly increased and their quality improved, since it will be understood that when the bars have once been assembled in

gangs, the bars 22 may be quickly and simultaneously inserted and positioned in the box and then secured in place by the insertion simultaneously of the bars 23. The bars 22 and 23, due to their complementary tapers, form moulding members of substantially uniform cross section across the cavities 12. The cavities are then simultaneously filled with sand, preferably by means of a blowing machine, though manual filling and ramming may be employed. When the cavities are filled with tightly packed sand, the tapered bars 23 are simultaneously withdrawn, thereby permitting the bars 22 to drop and freeing the characters 32 from the intaglio impressions made thereby in the packed sand. The bars 22 are then simultaneously withdrawn and the sand cores dumped from the box. When such a core is used for casting a sash weight, the metal entering the core aperture C forms a bridge or cross bar having a flat end bearing a character like the character 32 and the core portion B moulds the metal forming the walls of the eye to a curvature providing a non-abrading bearing for the sash cord.

Having described my invention, I claim:

Core-forming apparatus comprising a box having a plurality of sets of core cavities, a plurality of bars, each bar being insertable in a set of cavities, a connector for the bars and forming a handle for the manipulation thereof, a plurality of wedging bars adapted for engaging bars aforesaid for maintaining them in operative position, and a connector for the wedging bars forming a handle for the manipulation of the wedging bars.

Signed at Philadelphia, in the county of Philadelphia and State of Pennsylvania, this 25th day of Oct., 1926.

THOMAS HAROLD BROWN.
